UNITED STATES PATENT OFFICE.

CLAUDE M. GARLAND, OF COLLINGSWOOD, NEW JERSEY, ASSIGNOR TO CAMDEN IRON WORKS, OF CAMDEN, NEW JERSEY, A CORPORATION OF NEW JERSEY.

GAS-PRODUCER.

1,063,024.

Specification of Letters Patent.

Patented May 27, 1913.

Application filed February 27, 1912. Serial No. 680,336.

To all whom it may concern:

Be it known that I, CLAUDE M. GARLAND, a citizen of the United States, residing in Collingswood, county of Camden, State of New Jersey, have invented certain Improvements in Gas-Producers, of which the following is a specification.

The object of my invention is to simplify the construction of the means for breaking up the clinker and coke in gas producers. This object I attain by providing two or more fixed slicer bars, which break up the material as the body of the producer rotates.

In the accompanying drawings:—Figure 1, is a vertical sectional view of my improved gas producer on the line 1—1, Fig. 3; Fig. 2, is a vertical sectional view on the line 2—2, Fig. 3; Fig. 3, is a plan view; Fig. 4, is an enlarged vertical sectional view of one of the slicer bars; Fig. 5, is a sectional view of a slicer bar on the line 5—5, Fig. 4; and Fig. 6, is a sectional view of a slicer bar on the line 6—6, Fig. 4.

A is the base on which the producer is mounted.

B is the rotating body portion of the producer, having an ash hopper b, and extending up into the hopper from the base is a cone a having a cap a'.

C is an air pipe extending through the cone a. The hearth surrounding the cone is depressed and a water seal is formed between the hearth and the movable section B by a depending annular plate d which is attached to the base ring D of the movable section B.

The base ring section has an annular track d' on its underside which rests on a series of flanged friction rollers e adapted to bearings E, and attached to the periphery of this ring section D is an annular rack D' with which meshes a pinion f on a vertical driving shaft F driven in any suitable manner. This construction of the producer may be modified without departing from the essential features of the invention.

G is a fixed framework which supports the top section H above the body portion of the gas producer. This section is stepped as indicated; the portion H' being less in height than the portion H² and in the portion H² are the fuel openings. Mounted above these openings are the hoppers k, of any suitable construction. Near the upper end of the section H is the gas outlet h. In

the upper portion of the rotating body is an annular channel b' and extending into this channel from the section H is the annular plate h'. Water is supplied to this channel so that the joint between the body and top sections B and H is water sealed.

Extending through openings h² in the portion H' of the top section H is a series of slicer bars I. These slicer bars extend into the rotating section B of the producer and are for the purpose of breaking up the clinker or coke as it forms. These slicer bars are fixed and, as the section B rotates, they keep the coal in motion. Each slicer bar consists of a cast steel hollow shell in the present instance, and extending into which is a tube i which stops short of the bottom of the slicer bar, as clearly shown in Fig. 1, and at the upper portion of the slicer bar is a cap i' to which is attached the outlet pipe i'. Water passes through the central tube i and between it and the shell, and then out through the opening in the cap. Thus water is freely circulated in the slicer bar, preventing the bar from burning out.

I preferably make the portion I' of the slicer bar, which enters the material, oval in cross section, as shown in Fig. 6, while the body portion of the bar is preferably round, as shown in Fig. 5. This body portion is adapted to bearings n, n on the side wall of the upper portion H², and suitable means may be provided to prevent the bars turning.

The openings h² for the slicer bars are of greater diameter than the bars, as shown in Fig. 1, so that all of the strain of the slicer bars is taken by the bearings n—n and not by the walls of the openings.

m is a series of teeth cut in the upper section of each slicer bar.

M is a lever which engages the teeth m when it is desired to raise or lower the slicer bar. This lever is hung by a link m' from a bracket M' on the side of the section H. m² is a pivoted pawl which engages the teeth m and retains the slicer bar in any position to which it is adjusted. Other means for raising and lowering the slicer bar may be employed without departing from the essential features of the invention.

Each slicer bar is independently adjustable and, in the present instance, I have shown three slicer bars spaced different distances from the center of rotation of the

body section B, so that three annular paths are cut in the coking coal as the section B is rotated.

It will be understood that while I have shown a particular construction of the body portion of the producer and special means for driving the rotating body, the mechanism may be modified without departing from the main features of the invention.

10 By the above construction, it will be seen that I provide a simple and effective means for agitating the coking coal and preventing clinkering. As the body section rotates the bars not only part the coking coal into annular paths, but push the coal laterally and tend to break up any clinkers which may have formed.

By vertically adjusting the slicer bars they can be set to cut any depth desired, and 20 one may be set at a greater depth than another so as to insure the proper breaking up of the clinker and coke.

By securing the bearings of the slicer bars on the side wall of the upper section H, I 25 am enabled to make a very substantial support for the slicer bars, which will resist the pressure of the coking coal as the body portion rotates.

I claim:—

30 1. The combination in a gas producer, of a body section and a top section; means for rotating one in respect to the other; said top section being stepped to form upper and lower portions; a vertical wall between the 35 two; said lower portion having an opening therein near the vertical wall; a slicer bar extending through the opening into the body of the producer; and bearings for the slicer bar secured to the vertical wall.

2. The combination, in a gas producer, of a body; means for rotating the same; a top section inclosing the body and stepped to form upper and lower portions; a vertical wall connecting the two; the upper portion having a gas outlet therein and a fuel hopper thereon; the lower portion having a series of openings therein extending in front of the vertical wall; slicer bars projecting through the opening into the body of the producer; bearings secured to the vertical wall of the said top section for the slicer bars; means for vertically adjusting each bar in its bearing; means for locking each bar in the adjusted position; and means for circulating water through the several bars; said bars being supported by the bearings independently of the lower portion of the top section.

3. The combination in a gas producer, of a body portion; means for rotating said body portion; a fixed top section stepped to form upper and lower portions; a vertical wall; said lower portion having an enlarged opening therein near the wall; upper and lower bearings secured to the vertical wall; a slicer bar reciprocally mounted in the bearings and extending through the opening in the lower portion of the top section; said opening being greater in diameter than the bar so that the bar has no lateral bearing against the walls of the opening.

In testimony whereof, I have signed my name to this specification, in the presence of two subscribing witnesses.

CLAUDE M. GARLAND.
